CARD MAGAZINE

William W. Lasker, Brooklyn, N. Y., assignor to
Remington Rand Inc., Buffalo, N. Y., a corpora-
tion of Delaware

Application November 2, 1935, Serial No. 48,063

3 Claims. (Cl. 271—61)

This invention relates to improvements in machines which operate by the use of perforated data cards, and particularly to the magazine in which said data cards are stored pending their use by the machine.

Merchandise accounting systems have been developed in which a tag was perforated to show certain essential data such as stock item number, department number, value, and in the case of wearing apparel the size of the garment. In general, these accounting systems have required that when the merchandise was sold, the data portion of the tag was removed, and placed in an electrical transmitter, sometimes dubbed a "waffle iron", from which a punch for standard tabulator cards was actuated. It appears then, that if these tags could be utilized to operate a tabulating machine, and could be handled in a card sorting machine, an expensive feature of the system equipment could be eliminated. With this in view, tabulators and sorters have both been modified to handle the merchandise tag, which is a card of dimensions much smaller than those of the card heretofore used with these machines.

In carrying out the system as intended, it is necessary to run the tags through the machines before they are attached to the goods, and again after the sale has been completed. This means that the card magazine of both the tabulator and the sorter must be made adjustable as to the length of the card.

The present invention contemplates an adjustable card magazine for embodiment in a tabulator and/or a sorter, to permit the utilization of cards of different lengths, but of unaltered width.

The principal object of the invention is to provide a device for alternatively altering the length of a magazine for holding cards.

Another object is to provide manipulative means for securing an adjustable card magazine end in either of its alternative positions.

A still further object is to provide a manipulative device which may be latched in either its effective or ineffective position by means common to both positions.

The present invention contemplates a magazine for storing perforated records of differing lengths, comprising fixed members forming the ends of said magazine when cards of greater length are stored therein, a manipulative member forming one end of said magazine when cards of lesser length are stored, and common latching means for securing said manipulative

device in either effective or ineffective position.

Other objects and structural details of the invention will be apparent from the following description when read in connection with the accompanying drawings, wherein:

Fig. 1 is a front elevation of a magazine for storing perforated cards, showing the mechanism of the invention mounted thereon.

Fig. 2 is a section through Fig. 1 taken on the line 2—2.

Fig. 3 is a view of a card such as may be used with a machine equipped with the present invention.

Fig. 4 is a sectional view of the latching means.

Fig. 5 is an isometric view of the device latched in its ineffective position.

Fig. 6 is a view similar to Fig. 5, showing the intermediate position of the mechanism.

Fig. 7 is a view similar to Figs. 5 and 6 showing the device latched in its effective position.

In a machine which utilizes cards of the general character of a perforated record card, the magazine is provided with an end piece 10. This end piece, which usually is channel shaped, may be of any suitable material, and either cast or shaped from sheet metal.

The mechanism of the invention comprises, hinge butts 11, rivets 12, hinge strap 13, hinge pins 14, rivets 15, corner member 16, latches 17, knob 18, ball 19, and spring 20. The hinge butts 11 are slidably mounted on channel shaped end piece 10 by shoulder rivets 12. Each butt carries a hinge strap 13 secured to it in slidable relation by hinge pins 14. Spanning the hinge straps 13, and secured thereto by rivets 15, is an angle shaped corner member 16. Latches 17 are provided. Each latch is pivotally mounted on the front flange of end piece 10, and is provided with an operating knob 18 within which is a detent consisting of ball 19 and spring 20.

Let it be assumed that merchandise tags, such as are shown in Fig. 3, are to be passed through a machine. The angle corner member 16 is securely fastened, as shown in Fig. 5, by latches 17 being engaged over one leg of angle 16, and the detent balls 19 being entered in appropriate holes in the front flange of the channeled end piece 10.

If the data portion of the tags, that is, the portion shown to the left of the dotted line in Fig. 3, are to be passed through the machine, latches 17 are removed from engagement with angle 16 by the manipulation of knobs 18. Corner angle 16 is then moved straight to the front until hinge pins 14 rest in the notches at the rearward ends of hinge straps 13, as shown in

- Fig. 6. Latches 17 are then moved to the position shown, whereupon corner angle 16 is turned rearwardly about hinge pin 14, until hinge strap 13 rests against the front flange of end piece 10. 5 Latches 17 are then turned about their respective pivots until they have been returned to their previous positions. Corner angle 16 is thereby locked in the position shown in Fig. 7, and the magazine is set for handling cards of the lesser 10 length.

While I have described what I consider to be a highly desirable embodiment of my invention, it is obvious that many changes in form could be made without departing from the spirit of my 15 invention, and I, therefore, do not limit myself to the exact form herein shown and described, nor to anything less than the whole of my invention as hereinbefore set forth, and as herein-after claimed.

20 What I claim as new, and desire to secure by Letters Patent, is:

1. In combination with a device for varying the length of a perforated record card storage magazine, a plurality of latches for securing said 25 device in ineffective position, a plurality of hinge elements for guiding said device to effective po-

sition, and means integral with said latches for securing said device in effective position.

2. In a magazine capable of storing perforated cards of different lengths, the combination of 5 fixed ends for rendering said magazine suitable for storing cards of one length and a manipulative device for rendering said magazine suitable for storing cards of lesser length, said device being supported by one of said ends, and comprising a plurality of hinge elements for guiding said device to effective position, and latching means adapted to retain said manipulative device in either its effective or ineffective position.

3. A magazine for storing perforated record 15 cards of different lengths, comprising fixed members forming the ends of said magazine when cards of one length are stored therein, and a manipulative device supported by one of said fixed members for forming one end of said magazine when cards of lesser length are stored, said device 20 comprising a plurality of hinge elements for guiding said device to effective position, and latching means adapted to retain said manipulative device in either its effective or ineffective position.
